(57) **CLAIM**

The ornamental design for a bathtub caddy, as shown and described.

DESCRIPTION

FIG. 1 is a perspective view of a bathtub caddy, showing my new design within its environment in an assembled, unfolded and expanded configuration;

FIG. 2 is a front elevational view of the design of FIG. 1, shown isolated from its environment, the rear elevational view being a mirror image thereof;

FIG. 3 is a left-side elevational view of FIG. 2, the right-side elevational view being a mirror image thereof;

FIG. 4 is a top plan view of FIG. 2;

FIG. 5 is a bottom plan view of FIG. 2;

FIG. 6 is an exploded perspective view thereof, shown unassembled;

FIG. 7 is a top perspective view of the design of FIG. 2 in an assembled, unfolded and retracted configuration;

FIG. 8 is a front elevational view of FIG. 7, the rear elevational view being a mirror image thereof;

FIG. 9 is a left-side elevational view of FIG. 7, the right-side elevational view being a mirror image thereof;

FIG. 10 is a top plan view of FIG. 7;

FIG. 11 is a bottom plan view of FIG. 7;

FIG. 12 is a bottom perspective view of FIG. 7;

FIG. 13 is a perspective view of the main body portion of the bathtub caddy, shown in a folded and retracted configuration, isolated from the trays to show details of the design not clear from the fully assembled position;

FIG. 14 is a top plan view of FIG. 13;

FIG. 15 is a bottom plan view of FIG. 13;

FIG. 16 is a front elevational view of FIG. 13, the rear elevational view being a mirror image thereof;

FIG. 17 is a left-side elevational view of FIG. 13; and,

FIG. 18 is a right-side elevational view of FIG. 13.

The broken lines showing a bathtub and accessory holder in FIG. 1 depict environmental matter and form no part of the claimed design.
